(57) **CLAIM**

The ornamental design for an angle gage, as shown and described.

DESCRIPTION

FIG. 1 is a front and top perspective view of an angle gage; FIG. 2 is a back and rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The surface indicia (angles in degrees, etc.) illustrated in FIGS. 1-8 are exemplary only. These illustrated items form no part of the claimed design, and are hereby disclaimed.
